United States Patent Office

Des. 203,193
Patented Dec. 14, 1965

203,193

FISHING LURE

Carl Napier, 5643 3rd St., Mason, Ohio

Filed May 10, 1965, Ser. No. 85,215

Term of patent 14 years

(Cl. D31—4)

Fig. 1

Fig. 4

Fig. 2

Fig. 5

I claim:

The ornamental design for a fishing lure, substantially as shown.
